[57] **CLAIM**

The ornamental design for a profiled open disc for securing to a cylinder lock, as shown and described.

DESCRIPTION

FIG. 1 is a perspective view of the top, front and left side of a profiled open disc for securing to a cylinder lock showing my new design;

FIG. 2 is a perspective view of the top, rear and right side thereof;

FIG. 3 is a bottom plan view thereof;

FIG. 4 is a left side elevational view thereof, the right side being a mirror image thereof; and,

FIG. 5 is a top plan view thereof.
